UNITED STATES PATENT OFFICE.

FRANCIS M. SCHAEFER, OF CHICAGO, ILLINOIS.

DRIER.

1,216,504.

Specification of Letters Patent. Patented Feb. 20, 1917.

Application filed February 26, 1916. Serial No. 80,654.

To all whom it may concern:

Be it known that I, FRANCIS M. SCHAEFER, a citizen of the United States, residing at Chicago, in the county of Cook and State 5 of Illinois, have invented certain new and useful Improvements in Driers, of which the following is a specification.

This invention relates to certain new and useful improvements in driers, and has for 10 its object to provide a device by means of which damp sheets may be advantageously carried through a drying zone and delivered in a dried state in a perfectly flat uncurled condition.

15 The device is particularly designed and adapted for the drying of unmounted photographs and the like and it embodies means for receiving the damp photograph or other article as it comes from a 20 wringer, at which time it is in a perfectly flat condition, carrying the article in such condition to a drying zone and passing it through the drying zone while held between two traveling belts that the article will 25 be maintained flat as it is being dried, and finally delivering the article when dried, in flat condition.

In the drying of photographs, negatives, prints, etc., the material on which they are 30 taken has a tendency to curl up during the drying process so that when thoroughly dry, the sheet of paper or other material on which the print is taken has curled up substantially into roll form necessitating pressure being applied thereto for a considerable 35 length of time, or reverse rolling of the sheet to again flatten same, either of which operations oftentimes results in damage or injury to the print or other article.

40 By my invention I aim to wholly overcome this tendency of the sheet to curl during the drying operation, and I accomplish same by a novel construction of device, a practical embodiment of which is shown in 45 the accompanying drawings forming a part of this specification and wherein like numerals of reference are employed for designating like parts throughout the several views, in which:—

50 Figure 1 is a view in end or side elevation of a drier constructed in accordance with my invention, the supporting frame being in vertical section.

Fig. 2 is a front elevation of the device

with one of the drying chambers partly 55 broken away and partly in vertical section.

Fig. 3 is a top plan view of the device, the stand and receiving belt being broken away.

Fig. 4 is a horizontal sectional view taken 60 on the line IV—IV of Fig. 1, and,

Fig. 5 is an enlarged detail sectional view taken on the line V—V of Fig. 1.

To put my invention into practice, I provide a supporting frame 10, the side bars 65 of which at the back of the machine are extended upwardly to form a support for the mounting of a wringer 11, and also a drum 12 over which latter passes a belt 14.

The belt 14 also passes over a drum 15 70 having its shaft journaled in suitable bearings on the frame 10 near the front of the latter, and then passes vertically upward over a drum 16 and vertically downward 75 where it engages a spacing drum 17 and then passes around a drum 18 and to the drum 12. The drums 17 and 18 are journaled in suitable bearings carried by the frame 10 while the drum 16 is journaled in bearings carried by a rectangular top frame 19 that is supported by four corner rods or posts 20 that are in turn supported by the frame 10.

The frame 19 also carries, in juxtaposition to and at each side of the drum 16, drums 21, 22, a similar drum 23 being 85 tensionally mounted adjacent the drum 17 to coact with the drum 22. The mounting of the drum 23 is accomplished by the provision of a pair of supports 24 in the upper ends of which the drum 23 is mounted, these 90 supports extending through brackets 25 carried by the frame 10, a spring 26 and nut 27 providing an adjusting means for the drum 23 whereby to take up slack in the belt passing thereover.

A belt 28 passes over drum 15, under belt 14 on said drum and then passes upward vertically over drum 16, on top of belt 14 on said drum, and downward vertically to drum 23 around which it passes and then 100 passes upwardly and over drums 22 and 21 and downward vertically to drum 15.

The drums 16 and 17 are of a corresponding size, while drums 15—23 and 21—22 are of corresponding size, the described arrangement of the drums and the belts passing thereover providing two vertical passes or 105 passage-ways where the two belts 14—28 are

traveling in contact or engagement with each other from the top frame 19 to the supporting frame 10.

In the spaces between the vertically-extending portions of the belts 14 and 28 there are placed drying boxes designated at 29 for the outside boxes and 30 for the central box, the boxes 29 being spaced a slight distance from the middle or center box 30 in order 5 to provide the passes or passage-ways for the belts to travel therebetween. These boxes form chambers into which a drying medium or agent is introduced, such as steam, admitted through pipes 31, or the 10 drying medium or agent may be in the form of a fuel as gas, or an electrical medium placed in the boxes preferably adjacent the lower ends thereof. These boxes are closed on their sides, faces and lower ends, but are 15 preferably partly open at the upper ends in order to permit of sufficient of the drying medium or agent to escape and keep the drums 16, 21 and 22 heated to some extent 20 to effect a drying action upon the traveling belts passing over said drums. On their confronting faces, the boxes 29 and 30 are 25 preferably provided with vertically-extending grooves 32 which will allow any moisture that may be squeezed out of the belts 30 in the passes or passage-ways 33 (see Fig. 4) draining down the boxes.

These boxes are shown in the present illustration as supported by means of upper side supporting rods 34 and lower side supporting rods 35. These rods at their ends receive the upright supporting rods 20, the rods 34, 35 being supported on said rods 20 as by nuts 36. The rods 34, 35 extend into brackets 37 carried by the middle or center 35 box 30 and other brackets 38 carried by the side boxes 29. The central box 30 remains stationary, but the side boxes 29 are adjustable toward and away from the central box 30 so as to increase or diminish the width 40 of the passes 33. This adjustment is here shown as effected by means of sleeves 39 loose upon the rods 34, 35 and connected at their inner ends to the brackets 38. At their outer ends they have a swivel connection 40 with a hand wheel or nut 41 threaded on to the rods 34, 35. Thus, by turning the hand wheels or nuts 41 inwardly or outwardly, the boxes 29 are moved in corresponding direction toward or away from 45 the central box 30 and the width of the passes 33 thereby increased or diminished as desired.

The prints or other articles when discharged from between belts 14 and 28, at 50 the point just after passing rollers 17, 23, are delivered into a catch basket or any suitable device as 42 which may be carried on the front of the frame 10. An apron or drip catch 43 is preferably provided at the 55 base of the wringer 11 to prevent water

from the wringer rollers dropping on to the belt 14.

In operation, the prints or other articles in their wet condition as they come from the bath are passed between the rollers of the 70 wringer 11 and are received on to belt 14, which at this point is traveling downwardly at an incline toward drum 15. At this point, the print or other article is received between belts 14 and 28, and is carried upwardly in the first vertical pass 33, tightly and flatly gripped between the two belts, carried over drum 16 in this manner, and downwardly through the other vertical pass 33, and as the belts 14 and 28 separate to 80 pass respectively around pulleys 18 and 23, the prints or other articles are released and drop into the basket or other receptacle 42. A drying agent having been supplied to the boxes 29 and 30, the prints in their vertical 85 passage upward between the belts and in their corresponding passage downward in the same manner are carried through two highly heated drying zones, the prints or other articles themselves however, being protected from any direct effect of the drying medium, as they are flatly clamped between the carrying belts which act as a protector therefor during their passage through the two vertical drying zones.

The operation is a continuous one, being limited only by the capacity of the receiving belt, which may be at all times receiving the wet prints or other articles discharged as the carrying belts diverge to pass over the pulleys 18 and 23. By such a construction, all tendency of the prints or like articles to a curling or rolling action during the drying process is effectually prevented, and the print or like article is delivered in 100 a dry condition and perfectly flat and smooth as was its condition when received on the belt from the wringer. Although the wringer is here shown as mounted upon the frame 10, this is done to make the device a self-contained machine. Obviously, should the wringer be at a point removed from the machine, the prints or other articles can be placed by hand upon the inclined receiving portion of the belt 14 where 110 they will be carried through the drying zones in the same manner as above described. The drum 17 is in the nature of an idler, being employed at the base of the passage-ways 33, and of a diameter equal to the diameter 115 of the drum 16, so that the belts in their vertical travel in passes 33 will be held in engaging contact throughout such travel. Any adjustment of the belts necessitated is provided for by the mounting of the drum 23. The drums are preferably provided with means herein shown as flanges at the 120 ends thereof, that the belts may be kept true at all times to obviate any distorting of the prints or other articles between the belts 125 130

which might occur, due to any shifting of one belt relative to the other.

The shaft of drum 12 is driven in any suitable manner, either by hand or from a 5 suitable power supply.

While I have herein shown and described the specific embodiment of the invention involved, it is to be understood that in the practice thereof, various changes may be 10 made in the details of construction and arrangement of certain features of the invention, without departing from the spirit thereof as claimed.

What I claim as new is:—

15 1. In a drier, a supporting frame, upper and lower drums supported by said frame, two endless belts disposed to travel over said drums, spaced vertically disposed drying boxes forming passes therebetween through which said belts pass in their travel, the belts while in the passes contacting with each other to form carriers for articles between them, and adjusting means carried by the frame and engaging the boxes for 20 varying the width of the passes between the boxes.

25 2. In a drier, a supporting frame, a cen-

tral and a pair of side drying boxes supported above said frame, the side boxes being spaced from the central box to provide vertical passes therebetween, drums mounted at the upper and lower ends of said boxes, and a pair of belts traveling over said drums and through said passes, the belts while in the passes contacting with each other to form carriers for articles between them.

3. In a drier, a supporting frame, a driving drum and a plurality of lower drums carried by said frame, a top frame, upper 30 drums journaled in said top frame in vertical planes coincident with the lower drums, a pair of endless belts passing over said drums and traveling in face contact between the upper and lower drums, a central stationary and two adjustable side heating boxes arranged between the upper and lower drums and spaced to form passes through which the belts are carried in their travel, and means for adjusting the side boxes to 35 vary the width of the passes.

In testimony whereof I affix my signature.

FRANCIS M. SCHAEFER.
